US00D600352S

(12) **United States Design Patent**
Cryan

(10) **Patent No.:** **US D600,352 S**
(45) **Date of Patent:** **** Sep. 15, 2009**

(54) **BIOELECTRODE**

(75) Inventor: **Marc P. Cryan**, Maynard, MA (US)

(73) Assignee: **Neurometrix, Inc.**, Waltham, MA (US)

(**) Term: **14 Years**

(21) Appl. No.: **29/322,895**

(22) Filed: **Aug. 14, 2008**

(51) LOC (9) Cl. **24-02**

(52) U.S. Cl. **D24/187**

(58) **Field of Classification Search** **D24/168, D24/186-187, 200, 232; D13/182; 600/372-384, 600/391; 607/62, 109, 121, 139**
See application file for complete search history.

(57) **CLAIM**

The ornamental design for a bioelectrode, as shown and described.

DESCRIPTION

FIG. 1 is a perspective view of the bioelectrode;

FIG. 2 is a front side view, in elevation, of the bioelectrode, taken from the frame of reference of FIG. 1;

FIG. 3 is a rear side view, in elevation, of the bioelectrode, taken from the frame of reference of FIG. 1;

FIG. 4 is a left end view, in elevation, of the bioelectrode, taken from the frame of reference of FIG. 1;

FIG. 5 is a right end view, in elevation, of the bioelectrode, taken from the frame of reference of FIG. 1;

FIG. 6 is a top face view of the bioelectrode, taken from the frame of reference of FIG. 1; and,

FIG. 7 is a bottom face view of the bioelectrode, taken from the frame of reference of FIG. 1.
